RALPH REGINALD BOYLES AND EDWARD SANFORD STANLEY, OF ST. PAUL, MINNESOTA

SAFETY RAZOR

Application filed June 26, 1925. Serial No. 39,722.

Our invention relates to improvements in safety razors. In the present use of razors of the safety type a blade is either removed from a holder employed in shaving and transferred to a special honing and sharpening holder or retained in the original holder wherein the stropping only of the blade may be effected.

An object of our invention is to provide a simple, durable, efficient and inexpensive safety razor, the blade of which, without detachment from its holder, may be not only effectively stropped but honed through the medium of said holder.

Another object of the invention is to provide a safety razor including a holder and a blade structure hinged thereto, said structure being designed to provide for the uniform application of the cutting edge of the blade to the surface of a stone or strop and to prevent the mutilation or marring of such surface in the sharpening of the blade thereon.

A further object is to supply a holder and a blade pivoted therein together with yielding means to swing the blade into a certain position with respect to the holder and yieldingly hold said blade in such position, whereby the blade may be effectively manipulated, through the medium of the holder, in the stropping and honing of said blade.

With the foregoing and other objects in view, which will appear in the following description, the invention resides in the novel combination and arrangement of parts and in the details of construction hereinafter described and claimed.

In the drawings, Fig. 1 is a perspective view illustrating the front of a razor embodying my invention, said view showing the blade of the razor in position for shaving; Fig. 2 is a perspective view taken from the back of the razor; Fig. 3 is also a perspective view of the razor, the blade guard being swung back to free the blade; Fig. 4 is a central sectional view of the razor with the parts relatively positioned as in Figs. 1 and 2; Fig. 5 is a similar view, the parts having that relation shown in Fig. 3; Fig. 6 is an elevational view of the razor illus-

trating the manner in which the blade is applied to a strop or hone and Figs. 7 and 8 are fragmentary perspective views of alternate blade structures.

Reference being had to the drawing where-in like parts are designated by similar reference characters throughout the several views, it will be seen that we provide a holder or handle, yoke-like frame A including a shank 10 and a pair of branch supports 11 turned on said shank at right angles with respect thereto, a handle 12 being secured at one end to the shank 10 at the middle thereof. A blade structure B carried by the holder A includes a single edged blade 13 hinged at its ends to the supports 11, trunnions 14 on the ends of the blade 13 being fitted in complementing apertures in the tips of the supports 11 to effect the hinged or pivotal connection between blade and holder. Formed on the blade 13 (Figs. 1-6) back of each trunnion 14 is a shoulder 15, arranged to abut against its respective support 11 on either side thereof and limit the hinging action of the blade 13 on the holder A. The back of the blade structure B (Figs. 1 to 6 inclusive) comprises a roller 16 for blade inclining co-operation with a sharpening surface. This roller 16, which in effect constitutes an anti-frictional enlargement at the rear of the blade 13 is equipped at its ends with journal pins 17, said pins being journaled in ears or bearings 18 reaching rearwardly from said blade 13. The back of the blade structure shown in Fig. 7 is formed by rolling or beading the blade stock, as at 16^a while the back of the blade structure illustrated in Fig. 8 simulates, as at 16^b, the back of the usual "old style" non-safety razor.

The ends of the blade 13 forwardly of the trunnions 14 are recessed as at 19 and provided with studs 20. The extremity of one branch 21^a of a U-shaped tension spring 21 is caught over one of said studs 20 and the other branch of said spring 21 is likewise connected with the second stud 21, the body of said U-shaped spring having a medial loop 21^b formed therein and caught under a hook 22 secured to the frame shank 10.

A blade holding and guard member C com-

prises a metallic stamping including a body 23, a cam portion 24 at one side thereof, arms 25 at the opposite side, blade receiving clips 26 at the tips of said arms and a guard lip 27 between said arms.

Trunnions 28 formed at the ends of the body 23 and inserted in complementing apertures in frame supports 11 hingedly connect the guard member C to the holder frame. 10 A leaf spring 29 secured medially to the frame shank 10 and bearing at its ends against the cam portion 24 of the guard member C yieldingly holds said member in either of two positions, one a blade holding 15 position (Figs. 1, 2 and 4) and the other a position (Figs. 3, 5 and 6), wherein the movement of said blade is not interfered with by said member. In the first or operative position of the guard member C, the 20 corners at the sharpened edge of the blade 13 are sheathed in the clips 26, said blade being rigidly secured by said guard member against hinging movement on the holder A and in relative position for shaving, the cutting edge of 25 the blade 13 in such position being guarded by the lip 27 of the guard member. In the second or inoperative position of the guard member C, the lip 27 abuts the handle 12 (Fig. 5), said member in such position being 30 entirely clear of the hinged blade structure B.

When the razor is not in use the guard member C preferably occupies its inoperative position (Figs. 3 and 5). Freed from said member C, the blade 13 is swung by the spring 21 into protected position (Fig. 5) within the plane of the frame A and yieldingly held in such position.

To sharpen the cutting edge of the blade 40 13, the back of the blade structure B is pressed against a strop or hone in a light sweeping stroke over the sharpening surface, the handle 12 being held slightly inclined with respect to the sharpening surface. The 45 direction of movement of the razor over the sharpening surface of course must accord with the nature of such surface, that is to say, in honing, the sharp edge of the blade leads and, in stropping, said edge trails. Half 50 turns may be imparted to the handle 12 between each working stroke to present the opposite beveled portions of the cutting edge of the blade 13 alternately to the sharpening surface. In meeting the sharpening surface, 55 the roller 16 or other form of back is the first portion of the blade structure B to strike said surface, the sharpened edge of the blade being thereafter brought against said surface in the sharpening stroke. Upon lifting the razor 60 from a strop or hone, the spring 21 immediately swings the blade 13 into its protected position in the plane of the holder A (Fig. 5). Thus quickly retracted to a certain relative position in the frame, the blade 13 is 65 uniformly self-positioned preparatory to each

sharpening stroke thereof, the result being that the user may effect the sharpening strokes as rapidly as desired. In stropping a blade, a user properly should keep the handle 12 from passing beyond the perpendicular in 70 the direction of the working strokes over a strop, otherwise the blade may tilt to advance the cutting edge thereof. A safe-guard to save a strop against injury when the handle 12 is improperly inclined lies in the shoulders 15 on the blade 13. These shoulders, limiting the tilting of the blade 13 in said frame A, act within reasonable limits to prevent the blade from cutting a strop, when said blade is accidentally turned in a direction to advance the cutting edge in the sharpening stroke.

The roller 16 is tapered from the middle thereof toward its ends to insure the uniform application of the entire length of the cutting edge of the blade 13 to a strop or stone. Were the peripheral surface of the roller to be cylindrical instead of tapered toward its ends from the middle, any slight inaccuracy in construction throwing the roller out of parallelism with the cutting edge of the blade might result in unequal pressures of cutting edge portions against a strop or hone. The tapering of said roller, however, is in degree allowing for a diametric dimension at the 90 ends of said roller sufficiently great to over-reach the roller bearings or ears 18, whereby said bearings are prevented from gouging a sharpening surface upon the inaccurate presentation thereto of the blade structure.

Changes in the specific form of our invention, as herein disclosed, may be made within the scope of what is claimed without departing from the spirit of our invention.

Having described our invention, what we claim as new and desire to protect by Letters Patent is:

1. In a razor, a yoke-like frame including a shank and spaced supporting branches thereon, an elongated blade pivoted at its ends between and to the tips of said supporting branches, shoulders on the blade for engagement with said supporting branches to limit the swing of the blade in both directions, bearings at the back of the blade, a roller tapered toward the ends thereof and mounted in said bearings, a blade holding and guard member hingedly mounted on said supporting branches, a leaf spring mounted on the frame shank and co-operating with said guard member to retain the same in blade holding position and also in position freeing and clear of said blade, a U-shaped tension spring fastened medially thereof to said frame shank 110 and pivoted at its ends to the ends of the blade between the pivotal axis and the cutting edge thereof, said spring acting, when the blade is free, to swing said blade into the plane of the yoke-like frame and yieldingly hold said 115 120 125 130

- blade in such position, and a handle secured to the shank of said frame.
2. In a razor, a yoke-like frame including a shank and spaced supporting branches thereon, an elongated blade structure hingedly mounted between the tips of said supporting branches, and including a blade with a cutting edge thereon, a blade holding and edge guard member carried by the frame and movable into and out of position engaging and securing the blade angularly of the plane of the yoke-like frame, and a spring interposed between the frame and blade structure, said spring acting, when the blade is free from said member, to swing said blade into the plane of the frame and thus yieldingly hold the same with the cutting edge of the blade in protected position within the frame, and a handle for the frame.
3. In a razor, a frame, a blade structure hingedly mounted in said frame, yielding means for swinging the blade structure to locate the edge of the blade in a certain position with respect to and protected within the frame and to yieldingly hold the same in such position, a guard member for engaging the blade and holding the same against the action of said yielding means with the edge thereof in another position with respect to the frame, said member being movable to disengage the blade and clear the same in its swinging movements under the action of said yielding means.
4. In a razor, a yoke-like frame including a shank and spaced supporting branches thereon, an elongated blade pivoted at its ends between the tips of said supporting branches, means associated with the blade for inclining the same under application thereof to a sharpening surface, a member mounted on the frame and movable into and out of position guarding the edge of the blade, said member in said position serving rigidly to secure the blade against swinging movement on the frame, a tension spring fastened to the frame and to the blade, said spring acting, when the blade is clear of said member, to swing said blade into the plane of the frame and yieldingly hold the same in such position, a shoulder on the blade for engaging with one of said supporting branches to limit the swing of the blade against the action of said spring, and a handle for the frame.
5. In a safety razor, a blade manipulating holder, a blade having a sharpened edge and hingedly mounted in the holder, means associated with the blade for inclining the same on a sharpening surface, said blade being swung on an axis between the sharpened edge and the blade inclining means, and yielding means for swinging the blade to locate the cutting edge thereof in a certain position with respect to the holder, said means serving yieldingly to hold said blade with its cutting edge in such position.
6. A safety razor including a frame, a blade hinged at its ends to said frame, a roller for engagement with a sharpening surface carried by the blade at the back thereof, a blade holding and guard member hingedly mounted on the frame, yielding means adapted to hold said member in operative and in inoperative positions, yielding means interposed between the frame and blade for swinging the latter to locate the same in a certain angular position with respect to the former and yieldingly to hold said blade in such position, and a handle for the frame.
7. In a safety razor, a frame, a blade endwise hingedly mounted between the cutting edge and back thereof on said frame, said back being provided with a sharpening surface engaging member, a blade securing and guard member hingedly mounted on the frame, a spring co-operating with said member to hold the same in position guarding the blade and securing it against hinging movement on the frame, also to hold said member in position clear of the hinged blade, a spring interposed between the frame and blade for swinging the latter to locate the cutting edge thereof in a certain position with respect to the former and yieldingly to hold said blade with its cutting edge in such position, and a handle for the frame.
8. In a safety razor, a frame, a blade hingedly mounted to swing in said frame, a blade holding and guard member mounted on the frame and movable to free the blade, yielding means to swing the blade on the frame and yieldingly hold it in a certain relative angular position with the cutting edge thereof within and protected by said frame, and a handle for the frame.
9. In a safety razor, a frame, a blade hingedly mounted to swing in said frame, said blade being adapted to move from a guarded position within said frame to an exposed position for contact with an abrasive member, resilient means for swinging the blade normally into guarded position and means on said blade for engagement with the abrasive member to swing said blade from a guarded position to operative position on said abrasive member.
10. In a safety razor, a frame, a blade hingedly mounted to swing in said frame, said blade being adapted to move from a guarded position within said frame to an exposed position for contact with an abrasive member, resilient means for swinging the blade normally into guarded position, and means on said blade for engagement with the abrasive member to swing said blade from a guarded position to operative position on said abrasive member, said blade being adapted to swing in either direction and said engaging means operating to bring said blade in engagement with said abrasive member to sharpen either side of said blade.
11. In an article of the class described, a

holder, a blade hingedly mounted therein, the holder being relatively thin as compared to the width of the blade and forming a guard adapted to shield the cutting edge of the blade in one of its positions with respect to the holder, said blade being adapted to be swung forth and back through the guarded position thereof to expose the cutting edge of the blade at either side of the holder, yielding means for swinging the blade into said guarded position from oppositely disposed locations with respect thereto, said means serving yieldingly to hold said blade in said guarded position.

15 In testimony whereof, we have signed our names to this specification.

RALPH REGINALD BOYLES.
